UNITED STATES PATENT OFFICE

EARL V. HARLOW, OF JERSEY CITY, NEW JERSEY, ASSIGNOR TO THE KOPPERS COMPANY OF DELAWARE, A CORPORATION OF DELAWARE

LIQUID DISTRIBUTING APPARATUS

Application filed March 28, 1929. Serial No. 350,544.

This invention relates to a device for uniformly distributing a liquid over a given area and more particularly to a spattering means used in conjunction with a spray nozzle.

An object of this invention is to provide improved spraying apparatus particularly for use in scrubbing towers in connection with gas purification.

10 The apparatus of the present invention, which is of the type disclosed in Patent No. 1,597,715 to Blackburn, secures a uniform distribution of solution with widely varying circulation rates and nozzle pressures and is an improvement on the device disclosed in the said patent.

15 It has been found that in order to obtain the desired results, a device for the above purpose must be so constructed that the liquid will be sprayed uniformly over a given area and should not depend upon the adjacent sprays to cover the area directly in line with the nozzle. Furthermore, the spattering means must have no restricted sections which 20 would collect sulphur, or any refuse which is likely to be in the liquid treated.

25 The device must be capable of being easily rodded out in case of stoppage and must be rugged and rigid to prevent distortion while rodding. To resist the effect of corrosion, all 30 the parts are preferably made of metal such as heavy iron, aluminum or acid-proof bronze, or acid-resisting material such as hard rubber. If desired, metals coated with acid-resisting materials may be employed.

35 The spattering means which is the subject of this invention fulfills the above requirements. When a particle of liquid strikes a spatter plate of ordinary construction, it 40 tends to leave the plate along a tangent to the plate at the point of impingement. Therefore, with a plate having a surface of large radius of curvature, the liquid will be thrown off in a nearly horizontal direction and must 45 depend upon gravity for the downward motion.

Hence, if liquid strikes the plate at a high 50 velocity, the horizontal velocity component will be high compared with the vertical component and the liquid will tend to strike the

sides of the tower before it reaches the tower packing. However, when a spatter means is used having a surface with a small radius of curvature as, for example, a small ball, the tangent at the point of impingement is more 55 nearly vertical, which makes the influence of gravity relatively less and the total deflection of the particle more nearly independent of the velocity of the stream or rate of flow. With a ball of given size, even if the 60 size of the nozzle is increased slightly, the outside of the larger stream strikes the ball at a point where the tangent is still more nearly vertical and the deflection of the liquid is affected correspondingly less.

65 In the use of ordinary spatter plates, a considerable area beneath the plate receives no solution but must depend upon adjacent sprays to supply the solution. With a spatter means of substantially spherical shape, the 70 combined effect of adhesion and surface tension of the liquid sprayed, or in other words, capillarity, causes a part of the solution to follow the surface to the underside and be distributed upon the area directly beneath.

75 In the accompanying drawing:

Figure 1 is a view, partly in elevation and partly in cross-section, of the upper part of a scrubbing tower and showing the application of the device of this invention;

80 Fig. 2 is a view of the preferred form of spattering means;

Fig. 3 is a cross-sectional view on line III-III of Fig. 2;

85 Figs. 4, 5, 6, 7 and 8 illustrate various modifications of the spattering means and attaching means, Fig. 7 being a cross-sectional view on line VII-VII of Fig. 6.

The spraying device in general comprises 90 a nozzle 1 through which liquid is forced, and a spattering means 2 adapted to be placed in the path of the jet of liquid coming from the nozzle. The spattering means 2 is supported directly in front of the nozzle 1 by a 95 stirrup 3. The stirrup is so constructed that the position of the spattering means 2 may be adjusted with respect to the nozzle. The ends 4 and 5 of the stirrup 3 are threaded 100 to receive nuts 6, 7, 8 and 9 by means of

which the stirrup is rigidly clamped in place on flange 10 at the end of the nozzle 1.

Fig. 1 shows the use of the device in connection with a scrubbing tower 11 having an outlet 12. Any desired form of nozzle is directed into the top of the tower so as to project the liquid to be treated downwardly therein as, for example, through pipe 13.

The horizontal axial distance through the spattering means is preferably slightly greater than the diameter of the jet of liquid, for example, with a one and one-eighth inch nozzle a ball of approximately two inches in diameter and supported about four inches from the nozzle gives the desired result. With this arrangement, liquid rates of from 1000 gallons per hour to 4000 gallons per hour give satisfactory distribution.

The spattering means is preferably of spherical form and comprises a ball of corrosion-resisting material with a hole passing through the center thereof through which is passed a rod of relatively small diameter, such as rod 3, of similar material. The ball is welded to the rod and held in the middle thereof. The rod is bent on either side of the ball and the ends passed through the holes in the flange 10. The rod may be bent in any desired manner, as shown in Fig. 8. In order that the rod may cause the least interference with the flow of the liquid around the ball, it may be flattened for a short distance on either side, as shown in Figs. 2 and 3, or it may be shaped as shown in Figs. 6 and 7. This, however, provides only a slight improvement over the use of a round rod.

The spattering means shown in Fig. 4 is so shaped that the upper half of a cross-sectional view through the vertical axis is substantially similar to a Gothic arch and likewise the lower half in which latter case, the arch would be inverted.

In Fig. 5, a spattering means is shown with a flattened portion or belt 14, the upper and lower portions of the said means being portions of a sphere.

The spattering means shown in Figs 6 and 7 is so shaped that the upper and the lower halves are substantially bullet-shaped with the free ends pointing in opposite directions.

When the device is in use, the liquid impinges on the upper substantially spherical surface and is so deflected that a relatively small amount of the said liquid reaches the sides of the tower and the entire area directly below the spattering means and the immediate vicinity is uniformly sprayed with the liquid, thereby insuring proper distribution.

I claim as my invention:

In apparatus for treating gases with finely divided liquid, in combination, a shell, a liquid supply pipe passing through the upper portion of the said shell, the said pipe terminating in a downwardly directed nozzle within the said shell and adapted to pro-

ject a descending stream of liquid, a baffle having convex surfaces, and means rigid with the said shell for supporting the said baffle in the path of the said stream of liquid, the said baffle having an upper convex surface toward the said nozzle and a lower convex surface away from the said nozzle to bring about uniform distribution of the said liquid in finely divided form over an area within the said shell directly beneath the said baffle.

In testimony whereof, I have hereunto subscribed my name this 23rd day of March, 1929.

EARL V. HARLOW.
